BANK PROTECTION

William E. Cooper, New York, N. Y.

Application April 18, 1934, Serial No. 721,082

1 Claim. (Cl. 20—1.01)

This invention relates to the protection of banks from "holdups" and robberies.

Special objects of the invention are to enable such crimes to be stopped, without endangering 5 the lives of bank employees, patrons and others rightfully present; to provide apparatus for the purpose which can be readily installed, at no great expense, as a built-in portion of the bank structure, which will be proof against gas, as well 10 as the more used forms of attack; and to provide in cooperative relation with the actual protective means, mechanism for automatically recording events and for establishing identification of the bandits involved.

15 Other objects and the novel features, combinations and arrangements of parts which make up the invention are set forth in the following specification, illustrated in accompanying drawings and broadly covered in the claim.

20 The drawings referred to, show an illustrative embodiment of the invention, it being appreciated that many changes and modifications may be made, all within the true spirit and broad scope of the invention.

25 Fig. 1 in the drawings is a broken front elevation of the entrance to a bank or other structure to be protected, showing in particular the guard turret or tower immediately over the doors and giving full view to sidewalk and street in front of the bank.

Fig. 2 is a similar view from inside, showing how this tower also commands a full view of the interior of the bank or other structure.

Fig. 3 is a broken vertical sectional view down 35 through the turret, as on line 3—3 of Fig. 1, illustrating how it is set in the wall so as to give commanding views both ways.

Fig. 4 is a broken horizontal sectional view of the turret as on line 4—4 of Fig. 3.

40 Fig. 5 is a broken horizontal sectional detail as on substantially the plane of line 5—5 of Fig. 1.

45 As appears in the several views, the turret 1, is in effect a small guard room and sentinel post of bullet-proof construction, set in the wall 8 of the bank structure, so as to give view to both the interior and the outside of the structure. Placed directly over the main entrance 9, as indicated, a sentinel on watch, can observe what is going on 50 inside or out in front of the bank and can see who is entering and leaving.

55 The turret may be made as conspicuous or as inconspicuous as desired, and be only a small booth, substantially the thickness of the wall, or jut out at one or both sides, as shown. In shape

it may vary quite widely from the generally circular form shown but the latter is considered preferable because of the wider angle view both ways.

The windows may be arranged in different 5 ways. In the illustration, there is one long arcuate window 10, at the inside and a series of small arcuate windows 11, at the outside, all of bullet-proof glass.

The walls may be made of armor plate or equiv- 10 alent and are shown as double, with thermal insulation 12, between.

A temperature governing or air conditioning unit is indicated at 13, which, with the booth entirely closed to both the interior and exterior 15 of the building, may be used to furnish heat in winter and to cool the chamber in summer.

For ventilation and more especially for 20 countering gas attack, intake and exhaust ventilating fans 14, 15, are shown, oppositely placed preferably, such as indicated, one at the bottom, the other at the top and in diagonally opposite sections, so as to quickly fully sweep out the booth. Both are shown opening to the outside so as to handle fresh outside air. They may 25 be protected by grilles or be otherwise suitably covered, preferably in such a way as to prevent firing through the same from the outside. Thus entrance to the intake might be up between the double walls and the exhaust be covered by the 30 overhang of the inclined bullet-shedding turret top 16. A suitable switch or switches are provided for starting one or both fans separately or together and slides such as 17, may be placed for shutting the ventilating ports from the inside. 35

Access to the booth is had, in the illustration, by a concealed passage 18, up through one of the adjoining columns 19 of the building, at one side of the door. This passage is shown as containing a ladder 20 and as extending from a lower level such as the basement, up through the bank floor 21 and opening into one side of the booth. A door 22 at the top, secured by an inside lock or latch 23, controls this passage. With this construction a guard or guards may enter or leave the tower without people on the bank floor knowing it. 45

One or more firing ports 24 are provided but 50 it is intended, at present, that these be placed only at the outside, substantially as shown. This is so that a guard on duty cannot fire on bandits in the bank, which would in most cases cause bandits to start firing indiscriminately with consequent loss of life, but must wait until they are 55

leaving and can then be singled out and picked off as they pass out the door.

To insure that no escape is made by other exits, a push button or like control 25 is conveniently located in the booth to effect the securing of any other exit or exits. This same control, or a separate one, if desired, may be employed for sending in a silent alarm to the police. A telephone 26 enables the guard to keep in touch at all times with bank officials or others and an annunciator 27 may be provided for signaling the guard from different stations in the bank.

To record events as they occur, a wide angle moving picture camera 28 may be trained on the bank interior and this may be under the control of the same, or another push button 25, or the like.

Because of the greater accuracy an automatic rifle, such as indicated at 29, is preferred to a machine gun and there is shown associated with this rifle an automatic moving picture camera 30, which will point with the gun and record the action. The sights of the gun and camera may be so related that the aiming of one will effect the aiming of the other and the means for starting the camera may be placed so as to be conveniently actuated in the handling of the piece.

From the foregoing it will be seen that in case of a holdup or the like, the guard, by actuating one control 25, sends in a silent alarm to the police, locks any exits other than the main door and starts the camera to record the scene in the bank. Stationed so he can observe every action at the inside, he is ready to pick them off as the bandits pass out the main door and here again the scene is recorded, for identification and other purposes. The door 22 may be gas tight to preclude such an attack up the shaft 18 and the fans are available to sweep the turret with fresh air at any time. The conditioner or conditioners 13 enable the guard to keep comfortable at all times, shut off from the bank. The function of the police, with this system, would mainly be to keep people away from the front of the bank to leave the field clear for the guard and with proper coordination a situation may be handled without injury or loss of life to innocent parties. No attempt is made to trap the bandits within the bank so no cause is given for indiscriminate shooting. The presence of the turret over the

door is in effect a warning and deterrent to crime.

If desired, reflectors or periscopic devices may be located to enable the guard to see directly beneath the booth and hence the entire movements through the doorway. The same results may be accomplished by bullet-proof transparent panels in the floor of the booth. By the provision of a suitably located speaker connected with a microphone in the booth, the guard may give commands to the bandits, warnings to those on the street and otherwise direct matters.

While especially intended for the protection of banking houses it will be apparent that the invention is adapted to other than this particular use. Accordingly words and phrases employed herein are to be considered as used in a descriptive rather than in a limiting sense, except possibly as limitations may be required by state of the prior art.

The hidden passageway may also be closed off at the bottom to prevent the flooding of the same with gas fumes or the like. Other changes and additions may be made all within the true intent and broad scope of the invention.

The windows may be extended down or additional windows be placed in the sides of the turret to give view close to the outside wall of the building, so that one attempting to hide against the wall of the building may be observed by the sentinel on duty. Vertical extending windows at the sides also may be provided in the inner wall of the turret if the same are found desirable.

What is claimed is:

Bank and like protection, comprising in combination with the wall of a bank building having a doorway therethrough for passage of patrons into and out of the bank, a guard turret built entirely in said wall and immediately over said doorway, said turret having means providing view to both sides of said wall directly in line with travel through said doorway and way for gunfire to the outside of the wall for enabling guards stationed in said turret to observe operations directly in front of the door outside the bank and also within the bank and enabling constant watching of persons passing beneath the turret from within the bank through the doorway to the outside and the firing on such persons when outside in front of the bank.
